Sam H. Cole

United States Patent Office.

EDMOND RICHARDSON AND JAMES H. COLE, OF ADRIAN, MICHIGAN.
ASSIGNORS TO JAMES H. COLE.

Letters Patent No. 78,014, dated May 19, 1868.

IMPROVEMENT IN DEVICES FOR ROLLING ROOFING.

The Schedule referred to in these Letters Patent and making part of the same.

TO ALL WHOM IT MAY CONCERN:

Be it known that we, EDMOND RICHARDSON and JAMES H. COLE, both of the city of Adrian, in the county of Lenawee, and State of Michigan, have invented a new and useful Improvement in Method of Forming Roofing, and machine for making the same; and we do hereby declare that the following is a clear and exact description, which will enable others skilled in the art to make and use the same, reference being had to the accompanying drawings, and to the letters of reference marked thereon. In the drawings—

Figure 1 represents a perspective view of the rollers A and B and the frame F and handle H.

Figure 2 represents a perspective view of the same, and, in addition, the frame D E of the bed, and also the steel strips *i* and *l*.

Figure 3 represents an end view of the bed D E and steel strips *i* and *l*.

Figure 4 represents an end view of the same with the roller C placed in working position upon them.

The nature of our invention consists in the mode or process of manufacturing Jay J. Wiggins' Egyptian case-hardened marble, (patented December 4, 1866,) and also all other plastic material, into sheets for roofing by the rolling process.

To enable others skilled in the art to make and use our invention, we will proceed to describe our process, and the construction and operation of the devices which we employ therein.

First, we construct a sand-bed to form the groundwork on which to form the sheets, and this is accomplished in the following manner: Take two long, square sticks of timber, of suitable size, and bed them into the ground, parallel to each other, and a distance apart, from centre to centre, equal to the width required for the sheets, and between their ends fit in end pieces, thus forming a parallelogram. Through the middle of the upper side of the longer pieces, we insert steel strips of convenient width, and as far between them as the sheets are wide, as long as the timbers, and their lower edges embedded into the timbers far enough to support them up edgewise, the upper corner bevelled off on the outside to a sharp edge projecting above the timbers half an inch or more.

Next, we fill up the interior with sand, wet and packed down, and strike it off with a straight-edge.

We now run the roller C over it, as represented in fig. 4, the body of the roller extending as far below the top of the steel strips as is required for the thickness of the sheets.

The bed being now prepared, we next prepare the small roller B, which can be readily detached from the frame F by an adjustable pivot. This done, the roller is next wound with a sheet of felting or paper, which should be somewhat wider than the bed, and then placed back in the frame. The felting is then drawn over the roller A in the direction indicated by the arrows in fig. 2, and drawn around under the large roller, and all then placed at one end of the bed.

We now commence pouring the plastic material upon the bed, and at the same time move the roller A forward lengthwise of the bed, the felting forming the upper surface of the sheet, and occupying the position represented by the purple lines of fig. 2, the felting or paper being paid out by the roller B as fast as required by roller A. The roller A and the edges of the steel strips *i* and *l* cut the felting the required width.

The scrapers *o* in frame F take off the surplus material that may chance to adhere to the roller A, when not protected by the felting.

The top of the bed may be sprinkled with ground slate or marble, or any other material desired for a surface for roofs.

Sheets made of material not heated can be taken up immediately; if heated, they can be taken up as soon as cool.

Having thus described our invention, what we claim as new, and desire to secure by Letters Patent, is—

1. The method herein described of making sheets of Egyptian case-hardened marble, or sheets of any

similar material, by the application of the felting simultaneously with the rolling and pressing of the sheets, substantially as described.

2. The construction of the rolling-instrument shown in fig. 1, having the rollers A and B, the former being provided with shoulders, *m* and *n*, and scrapers, *o o*, substantially as and for the purposes set forth.

3. In combination with said instrument, we claim the frame D E, when provided with the cutters, *i i*, substantially as described and for the purpose set forth.

EDMOND RICHARDSON,
JAMES H. COLE.
